UNITED STATES PATENT OFFICE.

GEORGE H. DAWSON, OF BOSTON, MASSACHUSETTS, ASSIGNOR TO SERVICE BUREAU, INC., OF CAMBRIDGE, MASSACHUSETTS, A CORPORATION OF MASSACHUSETTS.

INDEX CARD.

Application filed July 26, 1926. Serial No. 124,887.

The invention relates to index cards and particularly to the construction of the tab or label holder of relatively stiff cards, such as are commonly employed as guides or dividers to separate into groups the cards, folders or other index matter constituting a so-called vertical index system.

The principal objects of the invention are to provide an improved form of tab having a large window opening permitting the display of an unusually wide label, the sight opening extending below the margin of the card in order that the tab will not project an excessive distance above the card and thus diminish its rigidity; to provide a tab of this character which is curved or bent rearwardly of the card to permit a clear view of the label inserted therein and to add stiffness to the assembled structure so that the tab is less likely to bend when pulled forward to permit removal of the folders behind the guide card; to provide a metal tab having serrated edges bent at abrupt angles to the body portion of the tab, thus furnishing short prongs adapted to engage the surface of the card to prevent the admission of paper sheets between the card and the tab, to provide an index card having a pair of projecting tongues at one margin defining the margins of a cut-out recess and a tab folded over said tongues and having a window opening embracing the card recess, the ends of the tab being closed by the card tongues so that an index slip inserted into the window at its lower margin is prevented from longitudinal slippage or accidental removal; and in general to provide an index holder, adapted for attachment to a guide card which is simple and economical of manufacture, yet durable and convenient in use.

In the accompanying drawings, illustrating several embodiments of the invention,

Fig. 1 is a front elevation of a card having one form of the improved tab applied thereto;

Fig. 2 is a fragmentary elevation showing the construction of the card shown in Fig. 1 prior to the attachment of the tab;

Fig. 3 is an enlarged vertical section on the line 3-3 of Fig. 1;

Fig. 4 is a view similar to Fig. 3 showing an optional type of construction; and

Fig. 5 is a fragmentary view similar to Fig. 1 showing a further modification in

structure and illustrating the manner of inserting a label within the tab.

The card body 6 is made of any suitable stiff sheet material, such as cardboard, fibre-board or the like, and is provided with integral spaced-apart tongues 7 which project from its upper margin. The opposed edges 8 of these tongues are substantially parallel and, in extension, define the vertical margins of a relatively deep, substantially rectangular recess or opening 9 cut from the card body. Opposed notches 10 are provided at the ends of the respective tongues and the outer edges or shoulders 11 of the latter are preferably curved as shown in Fig. 2. The upper margin of the card is also cut away at 12 adjacent the respective shoulders 11 to permit the tongues to be flexed rearwardly of the card for the purposes hereinafter explained, and a shallow recess 13 is stamped from the lower margin of opening 9 to admit a finger for the purpose of removing a label from the assembled structure, as will become apparent.

The tab or label holder preferably consists of a piece of thin sheet metal, such for example as brass, doubled or folded at 14 to provide substantially rectangular front and rear leaves 15 and 16, respectively. The lateral margins of the blank are preferably notched, however, at the fold so that the width of the tab at the fold line is considerably restricted. A window 17 of unusual width (in a vertical dimension in the drawings) is provided in the front leaf 15, adjacent the fold line 14. The lower margin of the window has a recess 18 corresponding to the card recess 13, and notches 19 are provided to furnish additional space at said margin for the insertion of a label within the window. As indicated in Figs. 3 and 4 respectively, the upper portion of the tab is preferably curved, or bent at an abrupt angle, rearwardly, before application to the card.

The edges of each of the leaves 15 and 16 are preferably serrated, providing relatively short, spaced-apart teeth 20 which are bent rearwardly of the respective leaves at abrupt angles thereto. It is preferred that the teeth of the front leaf have blunt points and register with corresponding teeth of the rear leaf in order that the card body 6 will not be weakened excessively when the leaves of the tab are fastened thereon. For

this purpose it is desirable that the tab be fashioned from a metal sheet, as aforesaid, but in other aspects of the invention it is obvious that different materials of the requisite stiffness may be satisfactorily employed, such for example as sheet celluloid or heavy cardboard.

When the tab is applied to the card, the folded leaves straddle the tongues 7 and 10 cover the card recess 9, the fold line 14 fitting between the notches 10, and the tab shoulders registering with and protecting the card shoulder 11, so that a smooth upper edge is presented by the assembled structure, 15 which is obviously agreeable to the touch of the user. Owing to the resiliency permitted by the cut-outs 12, tongues 7 are readily flexed or bent rearwardly to conform to the curve or abrupt angle of the upper 20 portion of the tab, shown in Figs. 3 and 4 respectively. With such construction, it is desirable that the curve or angle bend be imparted to the tab along a line parallel to the upper margin of the card but substantially below said margin, for example adjacent the lower edge of window 17, so that the index data appearing on a label placed within the window will be clearly visible 25 when the card is filed with others in a drawer or receptacle.

The tab may be secured to the card in the aforesaid position by rivets 21, or other suitable fastenings, and when so secured the leaves engage the front and rear faces of 30 the card body, teeth 20 biting into the card surface so that it is impossible for paper sheets or other objects to enter and catch therebetween.

A label or index slip 22 may then be inserted into the card recess or pocket 9 behind window 17 by passing it upwardly from the lower edge of the window between the notches 19. After passing over the lower edge of the window, the bottom margin of the slip will snap into place against the rear leaf of the tab, as shown in Figs. 3 and 4. If desired, a transparent celluloid cover piece 23 may also be inserted with the label, as illustrated in Fig. 5, so that the label will 45 be protected from moisture and soilage. When fully inserted within window 17, the label and cover are held in fixed position by the overlapping margins of the front leaf 50 at the top and sides, and abut the lower margin of the card body recess 9 at the bottom. Accidental endwise movement of the label is prevented by the abutting edges 55 of the card tongues, so that the indicia appearing upon the label is always visible 60 through window 17. The label, or label and cover together may easily be removed from the label holder by inserting a finger in the registering recesses 18 and 13 of the tab and card body, respectively, and grasping the 65 bottom edges thereof.

Although particular advantages reside in the card and tab construction above described, it is apparent that several features of this invention may be embodied in more simple forms of structure. For example, 70 Fig. 5 shows a card and tab applied thereto, having a large window opening and serrated edges, but omitting the cut-outs 12 in Fig. 1. In this modification the leaves of the tab are substantially flat without a rearwardly 75 curved or bent upper portion. Further changes in structural details may also be employed to suit particular needs without departing from the essence of the invention as defined in the appended claims. 80

It is thus apparent that by utilizing the constructions herein described an improved label holder for guide cards is provided, possessing the several advantages set forth as objects of this invention. The tab is exceptionally strong and durable in use, especially when it is bent rearwardly as in Figs. 3 or 4, is economical to manufacture and readily applied to the card body, and permits clear visibility of a much larger label than is possible in former devices of this nature. The card tongues not only close the ends of the folded tab to provide a dirt and moisture-proof pocket for the label, but in addition serve to protect the tab shoulders and, by filling the space between the tab leaves, relieve the tab of objectionable sharp, 95 projecting edges.

I claim:

1. An index comprising a card having 100 upstanding integral tongues spaced from each other at one margin, and defining a recess open at the top and a tab consisting of a folded piece of sheet material, providing front and rear leaves, attached to the card over said recess, said tab straddling the outer edges of said tongues, the tab being constricted in width at the fold line and the tongues having notches to receive the ends of said fold, one of the tab leaves having a window aperture, the card and tab providing a label-receiving pocket the ends of which are closed by said tongues. 110

2. An index comprising a card having upstanding integral tongues spaced from each other at one margin and a relatively deep recess intermediate said tongues, and a tab consisting of a folded piece of sheet material, providing front and rear leaves, attached to the card, said tab straddling the outer edges of said tongues and encompassing said recess, one of the tab leaves having a window adjacent the fold line and extending below said card margin, and a portion of said tab leaf overlapping said card recess to provide a label-receiving pocket, the upper portion of said folded tab being inclined rearwardly of the card from a region beneath the upper margin of the card to permit visibility of a label in 130

said pocket, a portion of said upper margin being cut away adjacent the outer shoulders of the respective tongues so that the tongues may be readily flexed rearwardly within the tab.

3. A guide card for indexes comprising a card body having a recess cut from the upper margin and opening through the top edge of the card body and extending below the top edge of the card body forming shoulders to prevent lateral displacement of a label inserted within said recess, and a tab formed of a folded piece of sheet material attached to the card body over said recess, the fold line of the tab being spaced above the top edge of the card body, said tab having a window opening opposite said card recess extending upwardly beyond the top edge of the card body and downwardly to approximately the lower edge of the card recess, the fold of the tab being adapted to prevent upward displacement of the label and the bottom of the card recess being adapted to prevent downward displacement of the label, the side margins of said window opening overhanging the card recess to provide side flanges for holding the label in the card recess behind the window opening, said side flanges being notched at the bottom corners of the window opening over the corners of the card recess to permit the insertion and removal of the label.

4. A guide card for indexes comprising a card body having a recess cut from the upper margin and opening through the top edge of the card body and extending below the top edge of the card body forming shoulders to prevent lateral displacement of a label inserted within said recess, and a tab formed of a folded piece of sheet material attached to the card body over said recess, the fold line of the tab being spaced above the top edge of the card body, said tab having a window opening opposite said card recess extending upwardly beyond the top edge of the card body and downwardly to approximately the lower edge of the card recess, the fold of the tab being adapt-

ed to prevent upward displacement of the label and the bottom of the card recess being adapted to prevent downward displacement of the label, the side and bottom margins of said window opening overhanging the card recess to provide flanges for holding the label in the card recess behind the window opening, said side flanges being notched at the bottom corners of the window opening over the corners of the card recess to permit the insertion and removal of the label.

5. A guide card for indexes comprising a card body having a recess cut from the upper margin and opening through the top edge of the card body and extending below the top edge of the card body forming shoulders to prevent lateral displacement of a label inserted within said recess, and a tab formed of a folded piece of sheet material attached to the card body over said recess, the fold line of the tab being spaced above the top edge of the card body, said tab having a window opening opposite said card recess extending upwardly beyond the top edge of the card body and downwardly to approximately the lower edge of the card recess, the fold of the tab being adapted to prevent upward displacement of the label and the bottom of the card recess being adapted to prevent downward displacement of the label, the side and bottom margins of said window opening overhanging the card recess to provide flanges for holding the label in the card recess behind the window opening, said side flanges being notched at the bottom corners of the window opening over the corners of the card recess to permit the insertion and removal of the label.

Signed by me at Cambridge, Massachusetts this 21st day of July 1926. 90

GEORGE H. DAWSON.
